UNITED STATES PATENT OFFICE.

FRED JOHNSON, OF LEICESTER, ENGLAND.

APPARATUS FOR USE WITH SOLE-LAYING PRESSES FOR BOOTS AND SHOES.

Application filed November 26, 1926, Serial No. 150,923, and in Great Britain November 26, 1925.

This invention relates to apparatus for use in the repair and manufacture of boots and shoes.

In the repair and manufacture of boots and shoes, half soles and soles are frequently attached by means of adhesive solution, cement or the like, and for carrying out this process there is usually employed a press which includes a screw or other pressure applying member and a sole support of resilient or semi-solid character.

The object of the present invention is to provide improved means for use in conjunction with a press of the known type to enable the metal lasts ordinarily stocked and used by the repairer or manufacturer, to be employed in the attachment of half soles and soles to boots and shoes in the manner aforesaid.

Accordingly the invention consists of a device which, solely by engagement with the usual socket in the heel or adjacent part of a metal last, transmits the pressure exerted by the screw or other pressure-applying member of the press to the last for the purpose of pressing the work upon the support.

An important feature of the invention is that the device is of such a form as to enable the pressure-applying member to act on it at different points in order that maximum pressure may be applied to the work at correspondingly different points according to requirements.

In the preferred form of the invention the device consists of an arm, bar or equivalent which is engaged by the aforesaid screw or other pressure-applying member and has at one end a butt which is formed or fitted with an element for insertion into the hole or socket in the heel or adjacent part of the last. When the said member is inserted into the hole or socket the butt rests upon the heel part of the last and the arm, bar or equivalent extends horizontally over the forepart in a rigid condition for transmitting the pressure as aforesaid.

In further describing the invention reference will be made to the accompanying drawings wherein:—

Figure 1 is a side elevation of a sole-laying press of the type before referred to with a convenient form of the improved device in use therein.

Figure 2 is a side elevation, and

Figure 3 is a plan of the said device per se. Referring to the drawings, the device

shown therein is intended for use in connection with a metal last, for example 5, having a rectangular hole or socket and comprises an arm or bar 1 having at one end a butt 2, 60 in which there is formed a rectangular hole or slot 6 to receive a metal strip or tongue 7. Since different metal lasts may have sockets of different sizes therein, one or more packing strips 8 of metal may be used in conjunction with the tongue so as to enable the effective width of the latter to be varied as required. For instance, if the device is to be used with a last having a socket requiring a projection of less width than that of the combined tongue and strips, one or more of the strips 8 can be moved up into the butt to reduce the width of the projection below the butt for insertion into the socket. The tongue 7 and strips 8 are slidable lengthwise 75

in the butt 2 so that they can be adjusted therein in accordance with the depth of the socket, such as 5^a, in the heel part of the last and thereby enable the butt to make contact, as is preferred, with the top of said part (as 80 shown in Figure 1) when the projection is inserted into the socket. A thumb screw 9 or equivalent is provided in the butt 2 for fixing by a binding action the tongue and strips in position after adjustment. If desired the tongue may be formed integrally with the butt instead of being detachable therefrom.

The bar 1 or equivalent may be provided with a series of countersinks 13 or it may be 90 grooved to receive the end of the pressure-applying screw or member which has its bearing in the cross bar 16 of the press supported from the base 16^a, by pillars 16^b. When, as represented in Figure 1, the device, last, and work, e. g. a shoe 14 to which a half sole 15 is to be applied, are inserted in the press, the pressure applying screw 17 may, by suitably positioning the work on the semi-solid sole support 18 of the press, be tightened down 100 upon the bar at any desired point thereon so that maximum pressure may be applied to the work where most needed.

It should be observed that the device herein described is in the form of a cantilever 105 adapted to engage the last socket and extend rigidly therefrom for transmitting the pressure to the last solely by means of such engagement, said device being thereby distinguished from pressure transmitting devices heretofore proposed for use in presses of the kind referred to, which devices have engaged the

work at another point, e. g. the forepart or heel seat, as well as the last socket. The improved device obviates the use of a toe rest or pad which is advantageous for reasons which will be manifest.

What I claim then is:—

1. For use in a sole-laying press having a pressure-applying member and a work support, a device to enable an ordinary metal last to be used in the sole-laying process, said last to be used in the sole-laying process, said device consisting of an arm provided with means for engagement with the usual socket in the last and to transmit, solely by such engagement, the pressure exerted by the said pressure-applying member, to the last to press the work upon the support.
2. For use in a sole press having a pressure-applying member and a work support, a device to enable an ordinary metal last to be used in the sole-laying process, comprising an arm adapted to take the pressure exerted by the aforesaid member, a butt on said arm having a hole formed therein, a tongue fitting into said hole, and means to secure the tongue in the butt, said tongue being adapted by engagement with the usual socket in the last to form a connection between the last and the arm whereby the latter can act as a cantilever to transmit the pressure to the last for pressing the work upon the support.

In testimony whereof I affix my signature.

FRED JOHNSON.
